UNITED STATES PATENT OFFICE

LOUIS LINK, OF NEW YORK, N. Y., ASSIGNOR, BY MESNE ASSIGNMENTS, TO NASHUA GUMMED & COATED PAPER CO., OF NASHUA, NEW HAMPSHIRE, A CORPORATION OF MASSACHUSETTS

TAPE SERVING MACHINE

Application filed March 15, 1929. Serial No. 347,404.

My present invention relates to strip or tape serving machines and more particularly aims to provide an improved mechanism for feeding, moistening and serving lengths of adhesive or gummed strip material, especially for package sealing and the like purposes. As to all common subject matter this application is a continuation in part of my copending application, Serial No. 226,366, filed Oct. 15, 1927.

In the drawings, illustrating certain embodiments of my invention,

Fig. 1 is a plan view of one form of machine for carrying out my invention, a portion of the cover being removed to disclose underlying parts;

Fig. 2 is a side elevation of the machine of Fig. 1;

Fig. 3 is a longitudinal cross-section;

Fig. 4 is a front end elevation with the cover elevated and a portion thereof broken off, and with the moistening device removed;

Fig. 5 is a vertical section in a plane immediately to the rear of the severing means, as viewed from the front of the machine, that is, from left to right of Figs. 1 to 3;

Fig. 6 is a detail sectional view on a larger scale illustrating certain tape guiding means;

Figs. 7, 8 and 9 illustrate certain modifications, Fig. 7 being a view similar to Fig. 6, Fig. 8 a view corresponding to the right hand portion of Fig. 3, and Fig. 9 corresponding to the upper portion of Fig. 5; and

Fig. 10 is a perspective view of a cross-support.

Referring now more particularly to the drawings, like numerals indicate like parts as in my said co-pending application. The machine as a whole is provided with a main frame or housing comprising the opposite side frames or members 1 and 2 and the intermediate floor members 3 and 4, the latter at the lower left portion of the machine as seen in Fig. 3. The side members 1, 2 are preferably of sheet metal and have supporting feet 5, 5, etc., provided with protective rests such as the rubber members 6, 6, etc. Said floor member 4 at the front of the machine 50 serves to interconnect the side members 1, 2 at that point, being provided for this purpose

with depending flanges 8 at its opposite sides secured to the respective side frames as by screws, rivets or the like.

The side frames 1, 2 are suitably connected at other points as by the screws 9, 10 respectively at the central and rear portions thereof, said intermediately located screw co-operating with a spacing pin 11 between the frames; see also Figs. 2 and 5.

The main floor member 3 and the side frames are constructed and arranged to provide a well or support for a roll of strip material, such as the adhesive or gummed tape indicated at 34, Figs. 2 and 3, said floor member also serving as an underlying support or guide for the tape as it feeds forwardly from the roll. At its rear end said floor member 3 is bent over to form a sleeve or spacer 13 which receives the screw 10 through it. From said point the floor member 3 extends downwardly and forwardly to provide the floor of the tape well, thence upwardly and forwardly to the feeding means, and up to or substantially up to the severing means, the latter including a fixed shear blade 15 extending across and above the floor member. At its forward end adjacent said fixed blade said floor member and tape guide 3 is supported by a cross-piece 16 seen in section in Fig. 3 and in perspective in Fig. 10, and which comprises a horizontal main portion having at its forward edge a depending lip 16^a around which the end of the floor member 3 is bent. Said cross-piece is also formed adjacent each side frame with a depending ear 16^b, see also Fig. 4, said ears being positioned against the adjacent face of the respective side frames and secured thereto as by screws, one of which is seen at 16^c, Figs. 2 and 4. At its left end said cross-piece is formed with an extension 16^d projecting outwardly through the left side frame 1 and adapted to serve as a support for the pivot of the movable blade 40 to be more fully described.

At the forward end of the main floor member or tape guide 3 is fixed an overlying tape guide or plate 18 having at its opposite sides depending flanges 18^a, 18^a for supporting it in proper spaced relation above the under-

guide 3 so as to receive and guide the advancing tape between them. Said flanges 18^a of the plate 18 are secured to the underlying guide 3 as by means of slots in the latter receiving bent over nibs on the under-edges of said flanges. The rear end of said upper guide plate 18, toward the right in Figs. 1 to 3, is inclined and recessed substantially as illustrated to provide the transversely spaced guide lips 19, 19, whereby the leading edge of the tape will be accurately entered between the upper guide 18 and lower guide 3.

The tape is preferably guided at its side edges during feeding. For this purpose as illustrated in Figs. 1 to 6, the under-guide or floor member 3 has a plurality of laterally spaced slotted formations 20, 20 etc. and 21, 21, etc. respectively at opposite sides of the center line of the tape path; see particularly Fig. 6. Said slot formations are respectively adapted to receive the movable guide members or clips 22, 23 supported upon a bar or pin 24 extending between the side members 1 and 2. Said bar 24 has a like plurality of groove formations 25 similarly spaced as said formations 20, 21 in the floor member.

Each of said guide members 22, 23 is formed with a vertical slot 26, see also Fig. 3, of a width corresponding to the reduced diameter of the bar 24 at its groove formations 25, thus providing said members with a pair of depending arm portions which, in the form illustrated, are connected at their lower ends. These guide members at said lower ends each have an enlarged continuation 28 of the vertical slot 26 adapted to receive the ungrooved portion of the bar 24. It will be understood that either or both of said guide members 22, 23 may be lifted until the bar lies in their enlarged openings 28, when they may be moved along the bar and dropped into the selected slot formation 20 or 21 of the underlying guide or floor member 3, their upper portions being received by the corresponding grooved formations 25 of the bar. The guide members are thus adjustable or shiftable for guiding relation with strips or tape of different widths.

The fixed shear-blade 15 previously mentioned is formed at its right end with a finger 36 supported in the adjacent side frame 2; see Figs. 1, 2 and 4. At its opposite end it projects outwardly of the left side frame 1 where it is secured to the extension 16^a of the cross-piece 16 as by means of the bolt 38, which latter also serves as the pivotal support for the cooperating movable shear-blade 40. As best seen in Fig. 4 said movable blade 40 is formed with an elongated slot 41 in which is received a roller 42^a on a pin or stud 42 near one end of a shear lever 43, the lower end of which is pivotally supported upon an ear 44 projecting upwardly from the front floor member 4, as by means of the pin or

bolt 45. Said shear-lever 43 has an angled extension 46 projecting outwardly through a suitable slot in the adjacent side frame 2 and adapted to be engaged by a suitable abutment or reinforcement member 47 carried by the main operating lever 48.

A tension spring 49, see Figs. 3 and 4, is connected at one end to the shear-lever 43, and at its opposite end, at a point preferably somewhat both lower and to the rear of its forward end is connected to one side frame, herein the left frame 1, as by means of a nib 50 stamped out and projecting inwardly from the latter. Said spring 49 is so arranged that it not only tends to maintain the shear lever and the movable shear-blade in their normal or depressed position substantially as illustrated in Fig. 4 but also exerts a pull upon the shear lever 43 and consequently upon the movable blade 40 laterally of the latter and toward the fixed blade 15, so as to afford a good cutting action for said cooperating blades. It will also be noted that the construction and arrangement is such that as the shear-lever 43 is moved by depression of its projecting arm 46, the point of operative connection between said shear-lever and the movable blade, the point where the lateral pull is exerted on the blade, gradually shifts toward the free end of the latter as the cutting action proceeds. Thus a proper shearing or cutting action is assured throughout the length of the blades and entirely across the tape or strip to be severed. Said cutting or severing means and associated parts are claimed in my said copending application Serial No. 226,366.

The moistening means as herein illustrated comprises a liquid reservoir or tank 51 received upon the front floor member 4 between the side frames 1, 2. It is properly positioned in a direction from front to rear as by means of ribs 1^a, 2^a turned inwardly at the front ends of the respective side frames and by the ear 4^a projecting upwardly from the floor member 4 at the rear of the reservoir. Said reservoir has an interior, downwardly extending tongue 52 preferably formed as a continuation of the front wall and having its lower end bent at an angle to form a seat 53 for the lower end of a brush moistener 54, the free ends of the hairs or bristles of which project upwardly into the path of the tape. Cooperating with the free or projecting end of the brush is a yieldably supported plate 55 having a collar portion 55^a receiving a pin 51^a whereby said plate is pivotally supported by and upon the reservoir. Said plate 55 is adapted yieldingly to engage the rear portion of the projecting brush and similarly to engage the under face of the tape as it comes from the severing means, and accurately guides it to the brush moistener. The interior tongue 52 serves also as a guard to prevent spilling of the liquid

from the tank during its insertion or removal, or to conduct any excess liquid back into the tank.

The strip feeding means as herein illustrated is of the feed wheel or feed roll type. The upper guide plate 18 is cut away as at 56, see Fig. 1, to receive the upper feed roll 57, which preferably is knurled, and is rotatable upon a pin 58 received at its opposite ends in slotted bearings in the respective side frames. Said upper feed roll is yieldingly urged into feeding relation with the lower feed roll 59 as by means of the springs 58^a, 58^a on the tape guide bar 24 and respectively 10 engaging the opposite ends of the pin 58.

The lower feed roll 59, as illustrated, is somewhat narrower but of larger diameter than the upper roll 57 and desirably has a similar knurled surface, a slot 60 being 20 formed in the floor member 3 to permit said lower roll to engage the under face of the strip to be fed. Said lower roll 59 is fast upon a cross-shaft 61 rotatably supported in bearings on the opposite side frames. As 25 best seen in Figs. 3 and 5, said shaft 61 is adapted to be turned, preferably through step-up gearing substantially as illustrated, from a gear 62 rigidly secured to a ratchet wheel 63, both mounted to turn freely on a shaft 64 also rotatably supported in bearings 30 on the side frames. The operating lever 48 is fixed upon one end of said shaft which projects outwardly beyond the adjacent side frame, herein the right frame 2. Fast on said shaft 64 is a ratchet arm or pawl carrier 65 having pivotally connected to it at 66^a a pawl 66. Said pawl is normally urged into engagement with the ratchet 63 as by means 35 of a spring 67 engaging at one end a pin 66^b upon an extension of the pawl 66 and supported upon and secured to a pin 65^a on the pawl carrier.

When the pawl 66, by movement of the operating lever 48, is brought into a certain position its projecting portion engages a fixed pin 68 upon the adjacent side member 1 which causes the pawl to be disengaged from the ratchet 63 during further movement of the operating lever. Thus further movement of 50 the ratchet and consequently of the feed rolls 59, 57 is prevented during continued movement of the operating lever in the same direction.

Means is also preferably provided whereby 55 different predetermined lengths of tape may be fed, moistened, and severed. For this purpose I have provided a device for limiting the upward or return movement of the operating lever 48. Extending through a 60 curved slot 71, see Fig. 2, in the side frame 2 is a limit bolt 72, see Figs. 1, 4 and 5, having fixed upon it a pointer or indicator 73 and also carrying a limit-bushing 74, a knurled adjusting nut 75 and a cover nut 76. By releasing the adjusting nut 75 the carrying bolt 65

72 and indicator may be variously positioned along the slot 71 to limit the upward movement of the operating lever as desired. An index graduated in units of tape length is preferably provided for cooperation with 70 the pointer 73, substantially as illustrated in Fig. 2.

The operating lever 48 is normally urged into its upward or inactive position as by means of the coil spring 77 surrounding and 75 supported upon the shaft 64 and having one end secured to the cross-pin 11 previously mentioned and its other end secured about the pin 65^a on the pawl carrier 65, with which pin the pawl spring 67 is also connected. 80

Removably overlying otherwise exposed portions of the guiding, feeding, severing and moistening means previously described is a cover plate 79. Said plate has at its forward or free end a downwardly and rearwardly or reversely bent guide portion 80 which is adapted yieldingly to rest upon the upper projecting end of the brush moistener immediately forwardly of the yielding plate 55 on the reservoir. Rearwardly of the moistener said cover plate 79 is extended as at 81 to constitute a further tape guide in cooperation with said underlying plate 55, terminating in an upturned lip adjacent the severing means. I have thus provided means carried by the cover 79 for accurately guiding the tape from the severing means or shear blades, in cooperation with the underlying plate 55, up to and across the brush moistener and for causing the tape to be fed past the latter in a yielding moistening relation therewith. Said cover, which normally encloses all parts of the mechanism above the tape guide and floor member 3, is provided at its rear with a sleeve or bearing portion 82 100 whereby it is pivotally supported upon a cross stud 83 upon the side frames. Said cover plate 79 may thus be swung upwardly at any time for inspection, cleaning, or other purposes and upon being again lowered immediately and automatically assumes its weight 105 and guiding relation with the tape and the brush moistener. 110

In Figs. 7 and 8 is illustrated a modified form of tape guiding means. The pin or bar 115 24' is supported in the side frames 1, 2, preferably rotatably, at any suitable position along the path of the tape, for example, as shown in Fig. 8 or at the location of pin 24 of Figs. 1 to 6. Said pin 24' has a plurality 120 of annular grooves 25', 25' adapted to receive balls 26', 26' pressed by springs 27', 27' in bores 28', 28' extending diametrically in the respective guide members 22', 23', illustrated as discs. These guide members may be shifted along the pin 24' as desired, the balls 26', 26' leaving the particular groove in which they are then received, against the action of their springs, but snapping back into locking 125 position in any selected groove. The guides 130

are thus adjustable to cooperate with strips or tapes of different widths.

Similar guide means may also be employed, either in connection with the mechanism of Figs. 1 to 6 or of the other figures, to assist in retaining the supply roll 34 in desired position. As shown in Fig. 8, a pin 31, corresponding to the pin 24' and having shiftable guides 32 similar to guides 22', 23', is carried on a presser arm 30 pivoted on the screw 10 at the rear of the machine and urged toward the roll by a spring 35.

In Fig. 9 I have illustrated a modified form of yielding support for the upper feed roll 57, also in accordance with my invention. As there shown said roll 57 is rotatable upon a pin 58' supported at its opposite ends in the side frames 1, 2, and which is of sufficiently small diameter and inherently resilient and is so arranged as to press the feed roll 57 against the lower feed roll 59, but is yieldable away from the latter to permit the strip or tape to be fed between the two rolls.

My invention is not limited to the illustrative embodiments herein shown and described, its scope being pointed out in the following claims:

1. In a machine for serving and moistening strip material, in combination, a frame including spaced side members, strip advancing means between said side members including a feed floor having its fore portion below the upper edges of said members, a reservoir having a brush moistener projecting therefrom into the path of the strip, strip severing means between said brush and the strip advancing means, and a plate pivotally supported upon the frame between said side members, said plate cooperating with said side members to provide a covering closure for said moistening and severing means and otherwise exposed parts of the advancing means, and having a forward portion adapted to effect yielding moistening engagement of the strip and said brush moistener.

2. In a strip serving and moistening machine, in combination, a support for a strip supply, upper and lower feed rolls for advancing the strip between them from the supply, strip moistening means at the forward or delivery end of the machine, strip severing means between said feed rolls and said moistening means, and a vertically movable cover plate extending in its normal or operative position from a point to the rear of the axis of said upper feed roll forwardly over the latter and over the strip severing means and the strip moistening means, said cover plate having a portion yieldably engageable with the upper face of the strip as the latter passes the moistening means, operatively to engage said means with the strip.

3. In a strip serving and moistening machine, in combination with a frame or housing, means to advance and deliver the strip,

a liquid reservoir adjacent the delivery point, a brush moistener projecting therefrom, a plate pivoted on the reservoir in position to rest against the upper rear portion of the brush and to guide the strip thereto by supporting engagement with its under face, and a second plate overlying the brush and said first plate and pivotally supported to urge the strip yieldingly into moistening engagement with the brush.

4. In a machine for feeding and moistening strip material, in combination, a support for a strip supply, upper and lower rotary feed members for advancing the strip between them from the supply, said members being mounted for relative yielding movement in a separating direction and being normally urged into strip advancing relation, strip moistening means at the delivery end of the machine, a movable blade to sever the strip between the feed members and the moistening means, and a vertically movable plate supported at one end portion to the rear of the feed members and having a portion at its opposite end adapted to depress the advancing strip into moistening engagement with the moistening means, said plate providing a top closure over the feed members and the movable blade.

5. In a machine for feeding and moistening strip material, in combination, a support for a strip supply, upper and lower rotary feed members for advancing the strip between them from the supply, one of said members mounted on an axial member having inherent resilience and positioned relatively to the axis of the other member yieldably to urge said members into strip advancing relation, strip moistening means at the delivery end of the machine, a movable blade to sever the strip between the feed members and the moistening means, and a vertically movable plate supported at one end portion to the rear of the feed members and having a portion at its opposite end adapted to depress the advancing strip into moistening engagement with the moistening means, said plate providing a top closure over the feed members and the movable blade.

6. In a machine for feeding and moistening strip material, in combination, a support for a strip supply, upper and lower rotary feed members for advancing the strip between them from the supply, variably positionable guide means cooperating with said feed members, for strips of different widths, strip moistening means at the delivery end of the machine, a movable blade to sever the strip between the feed members and the moistening means, and a vertically movable plate supported at one end portion to the rear of the feed members and having a portion at its opposite end adapted to depress the advancing strip into moistening engagement with the moistening means, said plate providing a top

closure over the feed members and the movable blade.

7. A gummed tape serving machine comprising, a shear device having a movable blade, an inverted brush moistener element for engaging the under face of the tape, and a combined pivoted cover and moistener-cooperative member adapted to be swung down over the shear to rest its free end on said moistener element, in the absence of tape, and carrying means to engage the upper face of the tape to press it into operative moisture-receiving relation to said moistener element.

In testimony whereof, I have signed my name to this specification.
